GOLF PLAYER'S MASK

Joseph E. Nero, Portland, Maine

Application March 5, 1941, Serial No. 381,805

5 Claims.

(Cl. 2—12)

My present invention relates to a novel device adapted to be worn by golfers to assist them in mastering the fundamental factors that control the correctness and accuracy of each stroke.

Golf is an extremely interesting and popular game, but one that is difficult to play well. Much has been written to inform players of the proper technique, but in spite of this readily available technical information, relatively expensive expert instruction is considered really essential to skillful playing.

In accordance with my invention, I present the factors, determinative of accuracy, visually to a player as he is making a shot and at the same time both facilitate the formation of correct habits and discourage the formation of habits destructive of accuracy. In brief, my invention consists of a mask-like device having an elongated aperture establishing a definite focal area through which the ball is visible when the player is positioned to hit it. At least one border line of the area is in parallel with the desired line of flight of the ball. The area exposes the head of the club in that portion of the swing in which it is essential that it travel in a path in alignment with the line of flight and the end borders of the aperture facilitate in the centering of the ball.

In my invention, the several factors that control the accuracy of the swing are visually established. Thus, the mask tends to keep the golfer's head down while the aperture facilitates the golfer in addressing the ball in a position correctly related to the desired line of flight. More specifically, the player assumes a position wherein the ball is centered relative to the ends of the elongated slot and by keeping the ball centered, the correct pivot on the proper axis is readily performed.

The long edge of the aperture visually defines a path along which the club head must travel to contact the ball properly. The ends of the pocket define the approximate limits of the zone in which the club head must follow this straight line both on the backswing and the follow through.

With these factors visually presented, the player quickly perceives the essential factors of a correct stroke and once these factors are appreciated, my invention assists correct strokes to become habitual.

In the drawing, I have illustrated an embodiment of my invention from which its general features and advantages can be readily appreciated. In the drawing:

Fig. 1 is a view showing a mask in accordance

with my invention as worn by a golf player in making a shot.

Fig. 2 shows the mask as viewed from the front, and

Fig. 3 is a rear view of the device shown in Fig. 1.

Fig. 4 shows diagrammatically the relation of the focal area to the factors controlling the accuracy of a shot.

As shown in the drawing, my invention consists of a mask comprising a sharply pitched front portion 1, sides 2 and a top 3 having its rear edge curved as at 4 to fit the brow of the wearer. The front portion 1 includes a straight bottom edge 5.

The sides 2 carry the elastic 6 by which the mask is secured in place. The elastic 6 may be conveniently inserted through slits 7 in the sides 2 thereby tightly anchoring the ends of the elastic 6, but permitting adjusting of its length if necessary.

The sides 2 carry supports 8 having a curved rear portion to engage the cheeks of the wearer adjacent the cheek bones. The front portion 9 of each of the supports is tapered and terminates rearwardly of the straight edge 5.

By this construction, I establish masks that may be worn over glasses and are adapted to be comfortably worn even by those whose features are irregular. The masks may be of any suitable material and either built up or molded in one piece.

In accordance with my invention, I provide a focal area defined by the edges of the front portions 9 of the supports 8, the front edge 5 and the exposed bottom edges of the sides 2.

In the illustrated form of my invention I provided a more limited focal area by a cross member 11 adjacent the ends 9 of the base supports 8 establishing an edge for the focal area in parallel with the edge 5 of the front portion 1. The member 11 may be an elastic or like band, as shown in the drawing, anchored in slots 11a in the sides 2 to permit it to be spaced from the edge 5 as desired by the wearer. While the member 11 may be otherwise formed and may consist of

two separate members spaced apart sufficiently to allow for unusual facial irregularities, but establishing the same limited focal area, a narrow band is preferable. Because of its proximity to the eye, it presents a border that does not obstruct the vision. For convenience, I have given the larger focal area the reference numeral 12 and the more limited slot shaped focal area the reference numeral 13. Although it is not es-

ential that the cross member 11 be employed, an

55

explanation of the utility of these areas justifies their separate identification. The focal areas thus established are of extreme importance in golf and in their relation to the factors determinative of the accuracy of a stroke may be best discussed in connection with Fig. 4.

In Fig. 4 I have indicated at 14 a golf ball having a desired line of flight 15. The position of the feet of a golfer is shown at 16 and it will be noted that their position is symmetrical with reference to a line 17 at right angles to the line of flight 15 and inclusive of the ball 14 when the stance of the player is such that the ball 14 is midway of the ends 2. The position of the ball 14 relative to the edge 5 is a matter of individual choice.

It will be obvious from Fig. 4 that my invention greatly facilitates correct stance since by bowing the head either the edge 5 or the edge of the cross member or members 11 may be shifted to establish a line 15^a parallel to the line of flight 15. In Fig. 4, the line 15^a demonstrates that the feet are properly positioned.

While the use of my invention in ensuring the proper stance is of great assistance, my invention also enables the factors controlling the accuracy of a stroke to be visually defined and presented as the stroke is being made.

To illustrate this feature of my invention, I have indicated in Fig. 4, a golf club 18, the head of which is in the focal area 13. It is essential to a correct shot, that in the start of the back swing, the club head be drawn back in part in alignment with the line of flight 15. The edges 5 or 11 permit the club head to be maintained in parallel until the club head passes from sight at which time the pivot is commenced. It will be appreciated that the hands and the club handle are visible in the area 12 and the limits of these areas help the player develop proper timing on the down stroke. As the stroke is being made, the club re-enters the focal areas in the same position in which it left. At this point, the hands are "uncocked" to increase the speed of the club head with the head in parallel with the edge 5. After impact with the ball 14, the club head continues along the line of flight in parallel with the edge 5 to establish a proper follow through and during the entire stroke, the mask assists in the player keeping his head down and steady.

My invention, by presenting the factors that determine the accuracy of the shot as the shot is being made, is of great assistance to golf players since it provides an inexpensive and accurate basis for mastering the correct technique of golf playing. My invention may be otherwise formed, but the embodiments of it herein described combine the several features for their complete appreciation.

What I therefore claim and desire to secure by Letters Patent is:

1. A mask to be worn by a golf player to visually present the factors determinative of the accuracy of the swing of a golf club in hitting a golf ball, said mask comprising a top and side portions, and a sharply pitched front portion, the

rear edge of said top portion being curved to fit the brow of the wearer, and inwardly disposed supports carried at the rear of each of said side portions adjacent its bottom edge for engagement with the cheeks of the wearer adjacent the cheek bones, said mask establishing a focal area inclusive of the ball when the player is properly positioned to hit it, said front portion including a straight edge constituting a visible border for said area parallel to the desired line of flight of the ball, and a narrow cross member carried by said side portions rearwardly of said straight edge in a position out of contact with the nose of the player establishing a second visible border for said area in parallel with said first straight edge and spaced from said front portion.

2. A mask to be worn by a golf player to visually present the factors determinative of the accuracy of the swing of a golf club in hitting a golf ball, said mask comprising a top and side portions, and a sharply pitched front portion, the rear edge of said top portion being curved to fit the brow of the wearer, and inwardly disposed supports carried at the rear of each of said side portions adjacent its bottom edge for engagement with the cheeks of the wearer adjacent the cheek bones, said mask establishing a focal area inclusive of the ball when the player is properly positioned to hit it, said front portion including a straight edge constituting a visible border for said area parallel to the desired line of flight of the ball, and an elastic band carried by said side portions rearwardly of said straight edge establishing a second visible border for said area in parallel with said first straight edge.

3. The device of claim 2 in which each of said side portions is provided with a plurality of slots to anchor said band in any one of a plurality of selected positions relative to said straight edge.

4. A device to be worn by a golf player to visually present the factors determinative of the accuracy of the swing of a golf club in hitting a golf ball, said device comprising a frame including side members, a front member defining a straight edge and a cross member carried by said side members rearwardly of said front member, said cross member being sufficiently small in size and being disposed sufficiently close to the eyes of the player when the device is worn to present a shadow line on opposite sides of which and in which the ball is visible and which shadow line demonstrates the line of flight.

5. A device to be worn by a golf player to visually present the factors determinative of the accuracy of the swing of a golf club in hitting a golf ball, said device comprising side members having a plurality of transversely aligned notches, and a cross member anchored in the transversely aligned notches selected to position said cross member as required by the player, said cross member being sufficiently small in size and being disposed sufficiently close to the eyes of the player when the device is worn to present a shadow line in which the ball is visible and which demonstrates the line of flight.
